UNITED STATES PATENT OFFICE.

JOSHUA B. BARNES, OF FORT WAYNE, INDIANA.

TWO-WHEELED VEHICLE.

SPECIFICATION forming part of Letters Patent No. 283,061, dated August 14, 1883.

Application filed March 2, 1883. (No model.)

To all whom it may concern:

Be it known that I, JOSHUA B. BARNES, a citizen of the United States, residing at Fort Wayne, in the county of Allen and State of Indiana, have invented certain new and useful Improvements in Two-Wheeled Vehicles, of which the following is a specification, reference being had therein to the accompanying drawings.

- 10 Figure 1 is a top plan view of a two-wheeled vehicle embodying my improvements. Fig. 2 is a side elevation of the same. Fig. 3 is a view of the equalizing-bar or hanger detached. Fig. 4 is a view of the rear brace for the side bars detached. Fig. 5 is a view of one of the side bars and a shackle which joins it to its shaft detached. Fig. 6 is a perspective of the bearing devices used at one end of the equalizing-bar or hanger.
- 15 In the drawings, A A represent the body, A' the seat, B the axle, and B' one of the wheels, of a two-wheeled vehicle, which parts may be of any preferred style. D D represent the thills or shafts, which, with the exception of the features to be hereinafter described, may also be of any of the ordinary styles. These parts, however—viz., the shafts, the body, and the axle—are connected together in an improved way, which I have devised.
- 20 C C represent side bars, which are situated by the side of and a little outside the body A. They are secured to the axle by means of blocks or metallic hangers, b, the latter having plates, b', which are firmly bolted to the under sides 25 of the side bars, and having clips or bearing-pieces, b'', firmly secured to the axle.
- The greater portions of the side bars, C, lie in front of the axle, there being, however, a portion of the same projecting in the rear thereof.
- 30 In order to prevent any spreading apart of these side bars from any of the causes which will be hereinafter mentioned, or which will be apparent, I employ one or more braces or strong connecting-rods, I. Each of these is fastened to 35 the side bars by means of clips i, and is provided with a drooping or bent portion, as shown in Fig. 4, to allow the body part of the vehicle to have sufficient room when a downward movement is caused.
- 40 At the forward ends the side bars, C C, are

curved upwardly, preferably to about the line shown in the drawings—that is to say, so as to lie between the upper and the lower edges of the body or box; but I do not wish to be limited to exactly that construction, as it can be 55 varied without departing from my invention.

At the front upwardly-curved ends, the side bars are provided with eyes C', by which they are pivotally connected to shackles H H on the shafts. When the side bars and shafts are 60 connected thus, the required motions and adjustments of one relative to the other will be permitted, as will be more particularly described.

The body has attached to it two or more 65 (preferably three) springs, F F, each of which is secured to the body in any suitable way, as by means of bolts and a block, and is at the ends fastened to the side bars, C C, by clips, in the common way.

The shafts D D are extended back of the shackles H, and back of the front end of the body A, and are curved downwardly at their rear ends, said ends consisting, preferably, of curved metallic bars J, firmly bolted to the 75 rear ends of the wooden portions of the shafts. These are extended downward and backward to a point sufficiently in rear of the front end of the body, where they are flexibly connected therewith, as follows:

E represents a rocking equalizing-bar or hanger. It is mounted on the under side of the body, and extends from side to side thereof. At the end it is formed or provided with plates or arms E' E', in each of which are formed 85 a series of pivot-holes, e. This equalizing-bar is loosely mounted in the bearings provided by means of a plate, G, and a recessed plate, G', which are bolted to the under faces of the side sills of the body, the parts E' lying 90 on the outside of the bearings. The rear ends of the shaft-extensions J J are pivoted in one or another of the apertures e by means of a bolt, e'.

It will be seen that when the parts of the 95 vehicle are joined together in the way which I have described the body is supported upon the side bars independently of the shafts, the springs providing the main supports.

It will be further seen that if there is any 100

sudden increase of weight on one shaft, or if by a jolt or otherwise the motion of one side should be arrested, there will be a tendency to rock the bar E, and as this is connected with the other shaft, there will be communicated thereto a portion of the strain or motion, and in this way there will be an equilibrium provided between them.

By means of the pivotal connections between the lower ends of the shafts and the equalizing-bar or hanger, sufficient flexibility between the body and the shaft is provided. The body can swing sufficiently, as the hanger or equalizing-bar can work backward and forward freely.

The front spring is secured to the body and to the side bars on a line midway between the connection of the shafts with the body and their connection with the side bars. This spring provides the main bearing for the body, and, being situated as described, there is at that point an equal amount of leverage on both of the couplings, the leverage being upward on the coupling at H and downward on that at E, or vice versa. Therefore the motion which would otherwise be communicated to the body is diminished, allowing it to remain comparatively level and free from the jerking motions characteristic of two-wheeled vehicles as heretofore constructed.

By having a series of apertures, e, in the plates or bars at the ends of the hanger or equalizing-bar, I can adjust the point of attachment of the shafts thereto so as to vary the positions of the outer ends of the shafts relative to the body, so that the shafts can be used with horses of different heights. I do not wish to be limited to the exact form in detail of the devices which I have shown in this respect, as they can be modified without materially departing from my invention.

The draft-frame can be united to the body by a single arm or bar, equivalent to those shown at J, if it be centrally or otherwise properly arranged, and this will give the necessary rigidity of connection between the body and the draft-frame, and also allow the necessary adjustment of one relatively to the other. I prefer, however, the construction shown when it is desired to have as perfect an equalization as possible of the motions upon the two sides of the vehicle.

When the parts are secured together, it will be seen that the side bars, C C, although being the immediate means of vertical support for the body, are also virtually a backward extension of the draft-frame, and constitute that by which said draft-frame is joined to the axle.

What I claim is—

1. A two-wheeled vehicle having the shaft united with the body by two pivotal couplings, one of which joins the rear ends of the shafts directly to the body above the springs, and the other of which is at a point farther forward on the shafts, and connects them with the body intermediately through the springs and

supporting devices below the springs, substantially as set forth.

2. In a two-wheeled vehicle, the combination of the body, the springs, the spring-support, rigid with the axle and below the springs, a hinge-connection joining the shafts at their rear ends directly to the body, and another hinge-connection joining the shafts at a point farther forward with the spring-supports, substantially as set forth. 70 75

3. In a two-wheeled vehicle, the combination of the axle, the side bars, C, formed separately from the shafts and secured rigidly to the axle, the springs secured to said side bars independently of the axle, the body resting upon said springs, and through them supported upon the side bars, and the shafts joined to the forward part of the side bars, substantially as set forth. 80 85

4. In a two-wheeled vehicle, the side bars, C, fastened rigidly to the axle and connected with the shafts, the body, cross-springs situated in front of the axle, transversely to the body, between the body and the side bars, and having their ends respectively attached to the latter, and the hinge which joins the rear end of the draft-frame with the body independently of the springs, substantially as set forth. 90 95

5. In a two-wheeled vehicle, the side bars, C, fastened rigidly to the axle and connected with the shaft by a hinge or hinges, the body, cross-springs situated in front of the axle, transversely to the body, between the body and the side bars, and having their ends respectively attached to the latter, and the hinge which joins the rear end of the draft-frame with the body independently of the springs, substantially as set forth. 100 105

6. In a two-wheeled vehicle, the side bars, C, fastened rigidly to the axle and connected with the shafts, the body, two or more springs between the body and the side bars, and the hinge which joins the rear end of the draft-frame with the body, and which is situated behind the forward spring, substantially as set forth. 110

7. In a two-wheeled vehicle, the combination of the body, the axle, the side bars situated below the bottom of the body, and the shafts united with the body by two pivotal couplings, substantially as set forth. 115

8. In a two-wheeled vehicle, the combination of the body, the springs, a spring-support resting upon the axle below the springs and extended upwardly above the bottom of the body and in front thereof, the shafts pivotally connected to the upward extension of the spring-support and pivotally connected with the body at a point in rear of said upward extension, substantially as set forth. 120 125

9. In a two-wheeled vehicle, the combination of the body, the springs, the spring-support secured to the axle below the springs and extended upwardly at or near the front end of the body to a point above the bottom thereof, the shafts joined to said upward extension of 130

the spring-support, and having their rear ends secured behind the front ends of the spring-support, substantially as described, whereby easy access to and egress from the vehicle are 5 permitted, substantially as set forth.

10. In a two-wheeled vehicle, the combination of the body, the springs below the body, the spring-support resting on the axle below the springs and extended upwardly above the 10 bottom of the body at the front end, and the shafts secured to the said upward extension of the spring-support above the bottom of the body and at a short distance behind the point of attachment, curved or inclined downwardly 15 to the point where their rear ends are secured, substantially as set forth.

11. The combination of the body, the side bars curved upwardly at their forward ends, and the shafts curved downwardly at their 20 rear ends and joined to the upper end of the upwardly-curved part of the side bars, substantially as set forth.

12. The combination of the body, the axle, the side bars fastened rigidly to the axle, and 25 curved, bent, or inclined upwardly at their forward ends, the springs interposed between the body and the side bars, and the shafts having downwardly-curved extensions at their rear ends, which (or the greater part of which) 30 downwardly-curved parts are situated above the horizontal parts of the side bars, substantially as set forth.

13. The combination of the side bars having upwardly-curved, inclined, or bent extensions 35 at their forward ends, of the shafts secured to the upwardly curved, bent, or inclined parts of the side bars and in rear of the points of attachment, having downwardly bent, curved, or inclined extensions, which (or the greater 40 part of which) are situated above the horizontal part of the side bars, substantially as set forth.

14. In a two-wheeled vehicle, the swinging or rocking equalizing-bar or hanger E, loosely connected with the body and joined at the ends with the shafts loosely, in combination with means for securing the shafts together and means for indirectly connecting the shafts with the body independently of said equalizing-bar, substantially as set forth. 45

15. In a two-wheeled vehicle, the swinging or rocking equalizing bar or hanger E, loosely connected with the body and joined at the ends with the shafts loosely, in combination with means for connecting the shafts with the body 50 at points other than the points at which the shafts are connected with the said equalizing-bar E, substantially as set forth.

16. In a two-wheeled vehicle, the combination of the body or seat support, the shafts, 55 each connected at its rear end with the body by a hinge or pivot, which can be raised and lowered, springs below the body, a support for the springs independent of the shafts, and a hinged joint for each shaft farther forward 60 than the adjustable hinged joint at the rear end and connecting it with the spring-support, substantially as set forth.

17. The combination of the shafts, the side bars hinged to the shafts, the body, the equalizing-bar or hanger E, and the adjustable supports carried thereby for receiving loosely the 70 ends of the shafts, substantially as set forth.

18. In a two-wheeled vehicle, the combination, with the body, of the shafts and the 75 means carried by the body for equalizing the strain upon the shafts, substantially as set forth.

In testimony whereof I affix my signature in presence of two witnesses.

JOSHUA B. BARNES.
